GADGET BAG

William H. Hinson, Waterloo, Iowa, assignor to Hinson Manufacturing Company, Waterloo, Iowa, a corporation of Iowa

Application June 4, 1956, Serial No. 589,174

5 Claims. (Cl. 150—52)

This invention relates to improvements in containers adapted for the storage and carrying of relatively small articles and more particularly to improvements in such containers adapted to be used with photographic equipment and the like.

The art of photography has developed to the point where even the casual photographer often finds it necessary to use relatively large amounts of equipment in his picture taking activities. Thus, the photographer frequently is loaded down with one or more cameras, a supply of film and a number of accessories such as a light exposure meter, folding tripod, interchangeable lenses, flash equipment, etc.

Many carrying cases have been devised in the prior art for accommodating this growing list of accessories and for providing safe storage for the generally easily damaged cameras. Customarily, these carrying cases, often designated as gadget bags, have ranged from small single pocket types to relatively large multipocket types to offer the user a selection consistent with the nature of his equipment.

In the manufacture of such carrying cases it has been found advantageous in some instances to provide the case with individual enclosures for the cameras and for the various accessories. Such an arrangement serves both to prevent the camera from being damaged by the accessories and in addition facilitates the picture taking operation. One disadvantage, however, in prior art carrying case constructions is that often the individual enclosures are disposed in crowded and interfering relation with each other so as to require the removal of the accessories to provide access to the camera.

It further has been found advantageous in the prior art to construct the carrying cases of a relatively soft and flexible material such as leather, Leatherette, plastic and other similar materials. This type of construction not only provides a pleasing appearance but additionally affords comfort and ease of handling to the user in the normal on the shoulder carrying position. However, this construction has the disadvantage of not providing as strong a protective enclosure for the camera as might be obtained by the use of more rigid materials.

It is a general object of this invention to provide an improved carrying case and storage container.

It is another object of this invention to provide an improved carrying case and storage container for photographic equipment which includes individual storage compartments for maintaining accessories in nondamaging relation to the camera.

It is still another object of this invention to provide such a container for photographic equipment wherein the accessory storage compartment additionally serves as a safety cover for the camera compartment.

It is still a further object of this invention to provide an improved photographic storage case which may be adjusted to accommodate cameras of different over-all size.

It is a still further object of this invention to provide

2

an improved photographic carrying case which has an individual and detachable accessory storage tray.

It is a still further object of this invention to provide an improved photographic carrying case having means for providing access to either an accessory storage compartment or a camera storage compartment while maintaining the other compartment in fully enclosed condition.

It is a still further object of this invention to provide 10 a unique photographic storage and carrying case which is characterized by its flexibility, compactness and structural rigidity.

These and other objects are realized in a specific illustrative embodiment of the invention wherein a carrying case for photographic equipment is provided with individually accessible storage compartments for cameras and for accessory equipment. In accordance with a feature of the invention the accessory storage compartment comprises an accessory tray which advantageously is formed 15 of a relatively rigid material and is detachably secured to the top cover of the camera storage compartment. A "zipper" is positioned between the camera storage compartment and its top cover such that access to the camera compartment is provided merely by opening the "zipper" and lifting back the cover.

In accordance with other features of the invention the top cover is made in two parts adapted to be separated from each other by a second zipper. The first part primarily comprises a strap having a number of snap fasteners attached thereto such that the accessory tray may be securely but detachably mounted within the strap above the camera compartment. The remaining part of the top cover comprises a lid adapted to fit over the tray and secured to the strap by means of the "zipper."

35 In practical use, therefore, the carrying case may be used to carry accessories in the storage tray or compartment and cameras in the camera compartment. Access to each is provided by means of a "zipper" located above each compartment without disturbing or opening the other compartment. If desired, the snap fasteners holding the accessory tray may be opened and the accessory tray removed from the carrying case for either transporting the accessories to a working position or for increasing the size of the camera compartment to accommodate a larger camera or an additional number of cameras.

Further, a pocket is provided on the front of the carrying case and a carrying strap is attached around the latter to facilitate transportation of the case.

The above and other features of novelty which characterize the invention are pointed out with particularity in the claims annexed to and forming a part of this specification. For a better understanding of this invention, however, its advantages and specific objects attained by its use reference is had to the accompanying drawing and descriptive matter in which is shown and described an illustrative embodiment of the invention.

Figure 1 is a perspective view of a fully closed photographic carrying case embodying the invention;

Figure 2 is a sectional view taken on line 2—2 of 60 Figure 1;

Figure 3 is a perspective view of the carrying case with the top cover open to provide access to the accessory compartment;

Figure 4 is a perspective view of the carrying case 65 with the top cover open to provide access to the camera compartment; and

Figure 5 is a perspective view of the upper rear portion of the camera case of Figure 1.

Referring now to the drawing, the specific illustrative 70 embodiment of the invention disclosed therein shows a photographic equipment storage and carrying case 10 which hereinafter will be referred to as a gadget bag,

Gadget bag 10 primarily comprises a camera compartment 12, a top cover 16 attachable thereto, a bag supporting strap 64 disposed around the sides of camera compartment 12 and held closely adjacent thereto by means of retaining loops 52, a carrying strap 56 attached to bag supporting strap 64 and a front pocket 40 having a protective flap 42.

Advantageously, the above described components are formed of a relatively flexible material such as leather, Leatherette, plastic or the like, to provide the gadget bag with a pleasing appearance and to facilitate the handling thereof especially when the gadget bag is carried over the shoulder of the user by means of carrying strap 56. However, it will be understood that any other material suitable to be used with such gadget bag may be utilized in its manufacture.

Top cover 16 in accordance with an important aspect of this invention comprises two individual and separately fastened portions. These include a tray support strap 22 and a lid 14. Tray support strap 22 extends substantially around gadget bag 10 and is connectable at its lower edge to camera compartment 12 by means of "zipper" 26. Tray support strap 22 further is connectable at its upper edge to lid 14 by means of "zipper" 24.

As best shown in Figure 2, tray support strap 22 has extending through the front portion thereof a pair of rivets 38 connected at their inner ends to clip springs 35 of a pair of snap fasteners 34. Tray support strap 22 has extending through the rear portion thereof a pair of rivets 18 connected at their outer ends to the back 15 of camera enclosure 12 and at their inner ends to clip springs 35 of snap fasteners 28.

An accessory tray 30 advantageously is detachably positioned within tray support strap 22. Rivets 37 and 36, extending through the front and rear walls of tray 30, are connected to flanged members 39 of snap fasteners 34 and 28, respectively. Thus tray 30 may easily be snapped into and out of supported engagement with strap 22, as desired.

It will be appreciated, therefore, that accessory tray 30 may be secured in position above camera compartment 12 to provide a receptacle for the storage of film, light exposure meters, lenses and the like or, alternatively, may be detachably removed by means of snap fasteners 28 and 34 from this position either to allow tray 30 to be utilized elsewhere than in gadget bag 10 or to provide additional space within camera compartment 12 for the accommodation of cameras of larger size or additional cameras. Further, it will be appreciated that when tray 30 is fastened to tray support strap 22, access to camera compartment 12 without disturbing the accessories in tray 30 is provided by opening "zipper" 26 and folding the entire top cover 16 back as shown in Figure 4 of the drawing. Alternatively, access to the accessories in tray 30 is provided without opening camera compartment 12 by undoing "zipper" 24 and folding lid 14 back as shown in Figure 3 of the drawing.

It is contemplated that tray 30 may be subdivided into as many compartments as desired by means of transverse dividers such as divider 32. Further, in a preferred embodiment of the invention tray 30 is formed of a relatively strong and rigid material such as wood, plastic or the like so that it may not only be used separate from gadget bag 10 but further safeguard the camera equipment in compartment 12 from damage as a result of a heavy object being dropped or being placed on the gadget bag.

Additional strength may be provided for the top cover of the gadget bag by means of a stiffener 60 attached to the upper portion 14 of lid 16. Additional strength may be provided for the rear wall of gadget bag 10 by means of a stiffener 62 attached to rear wall portion 15.

If additional storage space is desired it is contemplated that a pocket 40 may be attached to the front wall of camera enclosure 12. As shown in the drawing pocket 75

40 may have a flap 42 provided to cover the opening thereof and held in closed relation thereto by means of a tab 46 placed through a retaining loop 44.

Additionally it is contemplated that carrying strap 56 may be provided with buckle means 58 for enabling the length of strap 56 to be adjusted as desired in accordance with the user's preference.

It will be understood that the various components of gadget bag 10 may be connected by any desirable means such as stitching, riveting or the like or, alternatively, may be formed partially of integrally connected pieces and partially of stitched or riveted pieces of material. If desired a pair of camera supporting and cushioning bumpers 48 and 50 may be provided within camera enclosure 12 at the inner side walls thereof as shown in Figure 4 of the drawing. Manifestly bumpers 48 and 50 also serve to support tray 30 when the latter is fastened to strap 22.

While a particular embodiment of this invention has been described in detail it will be understood that this embodiment is merely illustrative of the application of the principles of the invention and that numerous other arrangements may be devised by those skilled in the art without departing from the spirit and scope of the invention.

What is claimed is:

1. A storage and carrying bag comprising the combination of a plurality of walls defining a relatively large enclosure, said walls being formed of relatively pliant material, elongated strap means disposed about certain ones of said walls for facilitating handling of said bag, strap retaining means attached to certain ones of said walls and forming loops thereat for holding said strap means to said bag, a cover for said enclosure, said cover including a lid and a strap, first "zipper" means disposed between said lid and one edge of said strap, second "zipper" means disposed between the top of the enclosure and the other edge of said strap, a tray formed of relatively rigid material adapted to be carried by said cover for utilization as a further storage means and as a protective cover for articles within said enclosure, access to said tray being provided by said first "zipper" means, and detachable fastener means attached to said strap and to said tray in cooperative relation for permitting said tray to be detachably positioned within said cover, access being provided to said enclosure when said tray is in position within said cover by said second "zipper" means.

2. A storage and carrying bag comprising the combination of a plurality of walls defining a relatively large storage enclosure, a cover for said enclosure, said cover including a lid and a strap, first "zipper" means disposed between said lid and one edge of said strap, second "zipper" means disposed between the enclosure and the other edge of said strap, a tray adapted to be carried by said cover, access to said tray being provided by said first "zipper" means, and detachable fastener means attached to said strap and to said tray in cooperative relation for permitting said tray to be detachably positioned within said cover, access being provided to said enclosure when said tray is in position within said cover by said second "zipper" means.

3. A storage and carrying bag comprising the combination of a plurality of walls defining a storage enclosure, a cover for said enclosure, said cover including a lid and a strap, first "zipper" means disposed between said lid and one edge of said strap, second "zipper" means disposed between the enclosure and the other edge of said strap, and fastener means attached to said strap and extending inwardly therefrom into said cover for attachment with a storage tray whenever the latter is positioned within said cover, access being provided to said enclosure when the storage tray is in position within said cover by said second "zipper" means.

4. A photographic equipment storage and carrying bag comprising a relatively large camera compartment, a

cover for said camera compartment, said cover including a lid and a strap, an accessory tray formed of relatively rigid material adapted to be carried by said cover means, detachable fastener means attached to said strap and to said tray for permitting said tray to be detachably positioned within said cover, first "zipper" means disposed between said lid and said strap for providing access to said accessory tray, and second "zipper" means disposed between said strap and said camera compartment for providing access to the latter when said accessory tray is fastened within said strap.

5. A gadget bag comprising the combination of a plurality of walls defining a relatively large camera enclosure, said walls being integrally formed of relatively pliant material, elongated strap means disposed about said walls for facilitating handling of said bag, strap retaining means attached to said walls and forming loops thereat for holding said strap means to said bag, a cover for said camera enclosure, said cover including a lid and a strap, first fastening means disposed between said lid and one edge of said strap, second fastening means disposed between the top of the enclosure and the other edge of said strap, a tray formed of relatively rigid material adapted to be detachably supported by said cover for utilization as a further storage means and as a protective cover for articles

5
10

within said camera enclosure whereby access to said tray is provided by undoing said first fastening means and moving back said lid and access is provided to said camera enclosure when said tray is in position within said cover means by undoing said second fastener means and moving back the entire cover, and third fastener means connected to said strap and said tray in detachable cooperative relation for enabling said tray to be detached from said gadget bag and thereby increasing the size of said camera enclosure.
